UNITED STATES PATENT OFFICE.

GEORGE OSBORN, OF LAKEVILLE, MASSACHUSETTS, ASSIGNOR TO HIMSELF, FREDERICK LEONARD, AND JOSEPH C. OSBORN, OF SAME PLACE.

IMPROVED NAIL-MACHINE.

Specification forming part of Letters Patent No. 92,994, dated July 27, 1869.

To all whom it may concern:

Be it known that I, GEORGE OSBORN, of Lakeville, of the county of Plymouth and State of Massachusetts, have invented a new and useful or Improved Machine for Making Cut Nails; and I do hereby declare the same to be fully described in the following specification and represented in the accompanying drawings, in which—

Figure 1 is a top view, Fig. 2 a longitudinal and vertical section, and Fig. 3 a side elevation of the machine.

The said machine has two sets of cutters or dies and a single vibratory nail-plate carrier, the latter during its operations being moved in the sector of a circle and alternately from one to the other of such sets of cutters, so as to introduce the strip of nail-plate to each of them in succession. By this combination there is avoided the necessity of turning the nail-plate over and back, as is necessary when only a single set of cutters—that is, a stationary bed-die and a movable cutter or die—is employed. With my invention a tapering nail-blank is severed from the strip immediately after the termination of each lateral movement of the nail-plate carrier. Furthermore, in this machine there is employed with the two sets of cutters and the vibratory nail-plate carrier what is termed the "intermediate guard," the purpose of it being to prevent the nail plate or strip during its passage from one set of cutters to the other from being accidentally forced into the space between the two movable cutters, so as to be improperly carried into contact with either cutter. This guard also directs the nail-strip properly toward that movable gage-guard against which at any time it may be in progress. There are also in the machine what are herein termed "movable gage-guards," there being two of them. The purpose of each is to direct the strip to the gages by which each nail-blank is sustained at its middle preparatory to being caught by the gripping mechanism and headed by the header.

In the drawings, A and B denote the two stationary or bed-cutters, arranged within sockets in a standard, C, erected on the bed-plate D of the machine. Placed between the pairs of cutters, and fastened on the upper surface of the standard C, is the intermediate guard, E, which is formed with a lip, *a*, extended up

from its inner end. The breadth of the guard at the top is equal or about equal to the distance between the two movable cutters F G, which are fixed in movable goose-necks or arms *b c*, pivoted to the bed-plate of the machine and arranged in manner as represented. These cutter-arms are provided with springs *d d* for raising them at the proper times. Extending across them, and having its journals sustained in bearings in the standards *e e*, is a cammed shaft, H, which carries two wipers or cams, *ff*, for operating or depressing the cutter-arms. To each set of cutters there may be mechanism for suitably holding or gripping the nail-blank and heading it after it may have been separated from the strip by such set of cutters. Such mechanism is shown in part in the drawings; but as it is like that commonly used in nail-machines, no further description of it is necessary.

The vibratory nail-strip carrier is shown at I. It consists of a spout terminating in a bow or arch, *g*, having a hole through its center for the passage of the nail-strip. Two springs or spring-jaws, *h h*, fixed to the bow *g*, are arranged therein and in the said hole in manner as represented. These springs embrace the nail-plate on its opposite edges and hold it with friction while the carrier may be at work. The carrier is pivoted to the top of a post, K, so as to be movable laterally. The front end of the carrier while in motion traverses across the bed-dies and the intermediate guard. The said carrier is also connected with a right-angular lever, L, which derives its motion from a pitman, M, that abuts against and extends through one arm of such lever, and is furnished with a spring, *k*, arranged in manner as represented. This pitman at its inner end is jointed to a pendulous lever, *l*, whose fulcrum is shown at *m*. The upper arm of the said lever *l* rests against the periphery of a cam, *n*, such cam being carried by the cam-shaft hereinbefore mentioned. A spring, *o*, fixed to the lever and resting on a stud, *p*, arranged as represented, serves to move the lever in the direction opposite to that in which it may be moved by the cam while the latter may be in revolution. By means of the said cam, lever, spring, pitman, and bent lever a reciprocating vibratory movement will be imparted to the strip-carrier while the cam-shaft may be in revolution, such move-

ment causing the nail plate or strip to be presented in succession to each of the pairs of cutters which are to be arranged and operated, so that at each presentation a wedge or frustum or tapering blank may be separated from the strip by their co-operative action during the downward movement of the upper cutter of the pair. By depressing the spring *o* the pitman may be caused to move freely within the arm of the bent lever without producing any movement thereof.

A nail-strip or piece of metal to be cut up into blanks for the formation of nails after having been run into and through the carrier will by such carrier, when the machine is in operation, be moved or vibrated from each pair of the cutters to the other, and provided the strip be suitably advanced in the meantime it will be gradually reduced to nail-blanks by the cutters. At or near the terminus of each lateral movement the strip will bring up against one of two lateral stops, *q q*, arranged on the stationary cutter-supporter in manner as represented. Each of the spring-jaws *h h* in its turn co-operates with one of the lateral stops in holding the nail-plate, although while the latter may be a lateral movement it will be held by both the springs. After having passed by the intermediate gage, the nail-plate will be forced against one of two movable gage-guides, *r r*,

which are shown in Fig. 4, such figure being a top view of them, the said gage, and the lower cutters. These gage-guards are two bent levers, which are pivoted to opposite sides of a standard, *s*, one of them being shown in Fig. 2. Their upper arms extend up in rear of the cam-shaft, and are operated by cams *t t*, projecting from such shaft. The said cams so actuate the levers as to cause their lower arms to rise, they at the proper times being caused to fall downward by the action of gravity or by springs suitably applied to them. The gage-guards prevent the plate from being advanced out of time, and are for the purpose as hereinbefore stated.

What I claim as my invention in the above-described machinery for cutting nails is as follows, viz:

The arrangement and combination of the movable gage-guards *r r*, (provided with mechanism for operating them, as described,) with the intermediate guard, *E*, the two series of cutters *A F B G*, and the vibratory nail-plate carrier *I*, the whole being essentially as set forth.

GEO. OSBORN.
